INVENTOR,

Louis Bagger & Co.

UNITED STATES PATENT OFFICE.

MICHAEL HOFFMAN, OF LORETO, PENNSYLVANIA.

SLED-BRAKE.

SPECIFICATION forming part of Letters Patent No. 254,318, dated February 28, 1882.

Application filed April 1, 1881. (Model.)

To all whom it may concern:

Be it known that I, MICHAEL HOFFMAN, of Loretto, in the county of Cambria and State of Pennsylvania, have invented certain new and useful Improvements in Automatic Brakes for Sleds, &c.; and I do hereby declare that the following is a full, clear, and exact description of the invention, which will enable others skilled in the art to which it appertains to make and use the same, reference being had to the accompanying drawings, which form a part of this specification, and in which—

Figure 1 is a plan or top view of the front bob of a sled or sleigh provided with my automatic brake. Fig. 2 is a longitudinal vertical section of the same; and Fig. 3 is a perspective detail view of one end of the transverse rock-shaft with its operating-arms and brake-rods.

20 Similar letters of reference indicate corresponding parts in all the figures.

My invention has relation to that class of sled-brakes which will set themselves as the sled goes down hill or when the team is suddenly stopped, while they are released or let go automatically when the sled is on level ground or going up hill, or when the team is started; and it consists in the improved construction and combination of parts, as hereinabove more fully described, and particularly pointed out in the claim.

In the annexed drawings, A represents the runners, B the knees, C the benches, and D the fenders, of a sled, or of the front bob of a sled.

E is the tongue to which the hitching-chain (not shown in the drawings) is attached, and which passes through a loop or keeper, F', secured in the front cross-bar, C', which prevents lateral play of the tongue without interfering with its free forward and backward motion. The rear end of the tongue is cut off abruptly, as shown at e, and has bolted to its under side a flat iron bar, G, the rear end of which passes through a keeper, h, and terminates in a cross-bar, H. At opposite ends of said cross-bar are links or rods I I, which connect with the downward-projecting arms K of a rock-shaft, L, which is hung in bearings M M secured in one of the benches C. That part of the rock-shaft between its bearings is made square in

cross-section, as shown in the drawings, for the purpose of the better attachment of its arms K, through the squarely-perforated heads of which the rock-shaft is inserted. At each 55 end of rock-shaft L, between its bearings M and arms K, is another arm, N, which projects at right angles, or nearly so, to the arms K. In the outer ends of these arms N are pivoted the brake-bars O, the lower ends of which are 60 inserted through keepers P, secured on the inner side of the runners, and are cut off obliquely to form the brake points or shoes p.

By reference to Fig. 2 of the drawings it will be seen that the brakes O are not set parallel 65 to the knees B, but slant or incline backward from top to bottom, for the purpose hereinafter set forth in describing the operation of the brake.

The bench C, immediately in front of the 70 cross-bar H, has a bolt-hole, Q, which is set to one side of the tongue-bar G, and the bottom of the sled, which is supported upon the benches, (but not shown in the drawings,) has a registering aperture, through which a headed bolt, 75 R, may be inserted into the bolt-hole Q.

When the sled is on level ground or going up hill the cross-bar H, upon which the strain of the draft comes, will bear against this bolt, and thus relieve the rods I I and rock-shaft L 80 from further strain. In going down hill or when stopping the team the front bench, C, will bear up against the cut off rear end, e, of the tongue, thus tilting the rock-shaft L, with its arms N, and forcing the pointed ends of the 85 brakes or brake-bars O down into the ground.

By setting the brakes O obliquely in the manner described, they will, when set as represented in dotted lines in Fig. 2, never be in a line with their connecting-arms N, so as to 90 form a dead-center, which, by the weight and downward pressure of the sled and its load, would be apt to bind, and thus affect the easy and instantaneous operation of the brake mechanism, and after the brakes have been once 95 set they and their operating mechanism are relieved from further strain by the rear end of the tongue E bearing against the front bench, C.

If desired, the rear end of the tongue which passes through the keeper F may be made 100 with two or more notches, f f, in its upper face, for locking it in any given position upon said

keeper by the means of a wedge inserted underneath it (the tongue) when it is desired to throw the brake mechanism out of play, or vice-versa. In backing the bolt R is removed 5 to permit the cross-bar H to pass the bolt-hole, after which the bolt is reinserted back of the cross-bar, which locks the brake in its "off" position and prevents setting. After backing as desired the bolt is of course reinserted in its 10 former position.

Having thus described my invention, I claim and desire to secure by Letters Patent of the United States—

In a sled-brake, the combination, with the 15 automatically-operating or self-setting brake

mechanism, composed of the oblique brakes O O, rock-shaft L, having arms N N and K K, connecting-links I I, T-shaped cross-head G H, and sliding tongue E e, constructed and arranged as described, of the movable bolt R, inserted vertically through the front bench, C, of the sled, substantially as and for the purpose herein shown and specified. 20

In testimony that I claim the foregoing as my own I have hereunto affixed my signature 25 in presence of two witnesses.

MICHAEL HOFFMAN.
